UNITED STATES PATENT OFFICE

171,924

INFRARED LAMP

Aaron Barkin, Bronx, N. Y., assignor to Practical Electric Products, Inc., Bronx, N. Y., a corporation of New York

Application May 19, 1953, Serial No. 25,111

Term of patent 7 years

(Cl. D48—20)

To all whom it may concern:

Be it known that I, Aaron Barkin, a citizen of the United States and a resident of New York, county of Bronx, and State of New York, have invented a new, original, and ornamental Design for an Infrared Lamp, of which the following is a specification, reference being had to the accompanying drawing, forming a part hereof.

Fig. 1 is a view in front elevation of an infrared lamp embodying my new design.

Fig. 2 is a view in side elevation.

Fig. 3 is a top plan view.

I claim:

The ornamental design for an infrared lamp, as shown.
